(57) CLAIM

The ornamental design for an electronic housing, as shown and described.

DESCRIPTION

FIG. 1 is a left, front perspective view of an electronic housing according to our novel design;

FIG. 2 is a rear, left perspective view thereof;

FIG. 3 is a rear view thereof;

FIG. 4 is a front view thereof;

FIG. 5 is a right side view thereof;

FIG. 6 is a left side view thereof;

FIG. 7 is a top view thereof; and,

FIG. 8 is a bottom view thereof.

The broken line portion of the figure drawings is included to show unclaimed subject matter only and forms no part of the claimed design.
